SUCTION NOZZLE

Adrian E. Ross, Stamford, Conn., assignor to
 Electrolux Corporation, New York, N. Y., a corporation of Delaware

Application January 12, 1940, Serial No. 313,521

4 Claims. (Cl. 15—156)

My invention relates to suction nozzles and more particularly to a suction nozzle of the duplex type.

In cleaning furniture, such as overstuffed furniture, a large portion of the surface of the fabric is relatively flat. However, there are areas which are sharply curved, as the arm of a chair or divan, and in addition there are corners and crevices where dirt is likely to collect. A suction nozzle which is provided with an elongated suction opening is useful for efficiently cleaning relatively flat surfaces. However, curved or arched surfaces present the difficulty that a portion of the suction opening will be completely uncovered, and so permit a large amount of air to flow into the suction nozzle without contacting the surface being cleaned. Also, difficulty is encountered when an attempt is made to clean a small corner or crevice, as one end only of the nozzle can be used to contact the surface being cleaned, and the effectiveness of the nozzle is reduced. Also, it is sometimes difficult to insert the nozzle into the corner.

In accordance with my invention, a duplex suction nozzle is provided with an elongated suction opening in one plane, which may be used for efficiently cleaning relatively flat surfaces, and a second suction opening formed in a different plane with a pointed end for ready insertion in confined spaces.

What I consider to be novel and my invention may be better understood by reference to the following specification and appended claims when considered in connection with the accompanying drawings, in which

Fig. 1 is a top view of my improved nozzle;

Fig. 2 is a sectional view taken along the line 2—2 of Fig. 1;

Fig. 3 is a sectional view taken along the line 3—3 of Fig. 2;

Fig. 4 is a sectional view similar to Fig. 2, with the nozzle in a different cleaning position; and

Fig. 5 is a front view of the nozzle taken from the left, as shown in Fig. 4, broken away in part to expose the parts beneath.

Referring to the drawings, 10 indicates a nozzle body having a cleaning face 11 with an elongated suction opening 12, and a second cleaning face 13 in a plane at right angles to the face 11, provided with a small suction opening 14 in a pointed end 15. Suction opening 12 is bounded on one side and its two ends by a smooth lip 16 formed in the body 10. The opposite side of suction opening 12 is bounded by a lip 17 formed in a plate 18 secured to body 10 by means of a plurality of screws 19, shown in dotted lines in Fig. 2.

The lips 16 and 17 are coplanar and form between them the suction opening 12 which is relatively long in proportion to its width. The lips 16 and 17 seal the suction opening 12 tightly against a surface of a relatively flat material, and due to the length of the opening 12 permit ready and efficient cleaning of a large area by covering a considerable width of strip in one continuous movement of the nozzle body across the surface. It may be found desirable in cleaning certain materials to use a brush 20, which is secured within the suction opening 12 by two spring clips 21, which extend over the lip 16 at spaced points.

For connection of the nozzle body 10 to the vacuum cleaner, or other source of suction, a tubular socket member 22 is provided and pivotally connected to the body 10 on an axis parallel to the lengthwise extent of suction opening 12. Socket member 22 is provided with a cylindrical portion 23 which is received in a correspondingly shaped cavity 24 in nozzle body 10. Cylindrical portion 23 is provided with two end closure plates 25 and 26, which are in turn provided with recesses 27 and 28 respectively, and cut-out friction spring fingers 29 and 30. Spring fingers 29 and 30 serve to hold the body 10 and socket member 22 in any desired relative position, such as in the position of Fig. 2, or in the position of Fig. 4. Socket member 22 is secured in position in cavity 24 by means of plate 18. Socket member 22 is provided with an opening 31 which communicates with the suction opening 14 when in the position of Fig. 2, and communicates with the suction opening 12 when in the position of Fig. 4.

Suction opening 14 is provided with a forward lip 32 in the pointed end 15 of body 10, as best indicated in Fig. 5. The lip 33 formed in plate 18 extends transversely of the face 13, and forms a rear lip for the suction opening 14. The area of the suction opening 14 formed between the lips 32 and 33 is relatively small, and due to the shape of the end 15 may readily be inserted in small crevices and confined spaces. In addition, the width of the suction opening 14 is so relatively small that the lips 32 and 33 can simultaneously contact a surface of arched or curved shape. This permits ready and efficient cleaning of such arched and curved surfaces, as are found on the top and arms of overstuffed furniture.

With this duplex nozzle, furniture may be readily cleaned by positioning the nozzle body 10 on the socket member 22 in the position indicated in Fig. 4, with or without the brush 20. When the nozzle is connected to a source of suction, the air flows over the surface adjacent

the face 11 in contact with the suction opening 12 through the opening 31 to the vacuum cleaner. When the large areas of the furniture have been cleaned and corners are reached which cannot be cleaned with the elongated suction opening 12, or it is desired to clean the arms or other curved surfaces, the nozzle may be positioned in its alternate position, as shown in Fig. 2. The small suction opening 14 and pointed end 15 can then be inserted in such corners, or in contact with such curved surfaces. The air then flows across the surfaces being cleaned into the suction opening 14 and through the opening 31 to the vacuum cleaner connected to the nozzle.

From the foregoing, it may be seen that by the construction of my improved nozzle, fabric covered furniture may be readily and efficiently cleaned with a single nozzle, using the elongated suction opening for cleaning large flat areas and using the pointed end with the small suction opening for cleaning in confined spaces and on curved or irregular surfaces.

What I claim is:

1. A duplex suction nozzle including a hollow body member, a flat face on said body member having an elongated suction opening, a second face on said body member extending at an angle to said first face having a dissimilar suction opening, a tubular handle socket pivotally connected to said body on an axis parallel to the lengthwise extent of said elongated suction opening, and friction means secured to said socket for holding said socket member in position relative to said body member in communication with one or the other of said suction openings.

2. A duplex suction nozzle including a hollow body member having an elongated face in one plane and a flat face in another plane, a plate secured to said body member bounding an elongated suction opening in one face and a small

5 suction opening in the other face, a socket member adapted for connection to a source of air flow secured to said body member by said plate having an opening communicating with one of said suction openings in one position and the other of said suction openings in another position, and friction means secured to said socket member for holding said socket member in one or the other of its selected positions.

10 3. A duplex suction nozzle including a hollow body member having an elongated flat contact surface in one plane and a flat surface in a plane at right angles thereto, a plate secured to said body member bounding an elongated suction opening in the elongated surface and a small suction opening in the other surface, a socket member secured within said body member by said plate, said socket member pivotally secured to said body member and having an opening communicating in one position with one suction opening and in another position with the other suction opening, and resilient means secured to said socket member and engaging said body member to hold said socket member in a selected position.

15 4. A suction nozzle including a body member having a central cylindrical cavity and an opening communicating therewith, a socket member having a tubular portion extending through the opening and a cylindrical portion seated in the cavity of said body member, caps secured to the ends of said cylindrical portion having struck out fingers frictionally engaging said body member, and a plate secured to said body member 20 for holding said socket member in position and defining with said body member an elongated suction opening in one plane and a dissimilar suction opening in another plane.
